UNITED STATES PATENT OFFICE.

WILHELM HERZBERG, OF BERLIN-WILMERSDORF, AND OSWALD SCHARFENBERG, OF BERLIN-SCHONEBERG, GERMANY, ASSIGNEES TO ACTIEN GESELLSCHAFT FÜR ANILIN FABRIKATION, OF BERLIN, GERMANY.

ORTHOXYAZO DYES.

1,408,297.

Specification of Letters Patent. Patented Feb. 28, 1922.

No Drawing.

Application filed November 5, 1921. Serial No. 513,171.

To all whom it may concern:

Be it known that we, WILHELM HERZBERG and OSWALD SCHARFENBERG, citizens of the German Republic, residing at Berlin-Wilmersdorf, Germany, and Berlin-Schoneberg, Germany, our P. O. addresses being Prinzregentenstr. 10, Berlin-Wilmersdorf, Germany, and Rosenheimerstr. 12, Berlin-Schoneberg, Germany, have invented certain new and useful Improvements in Orthoxyazo Dyes, (for which we have made application in Germany Jan. 8, 1920, and Oct. 27, 1920,) of which the following is a specification.

Our present invention relates to new orthoxyazo dyes which may be obtained by combining a polyhalogen-2-diazo-1-oxyderivative of the benzene series with an acidyl-aminoxyphthalene sulfonic acid. These new dyes form in the dry pulverized state of their sodium salts dark powders soluble in water with blue to violet color, the aqueous solution becoming more reddish by addition of sodium carbonate and red by addition of sodium hydroxide, by an acid a violet-red precipitate being separated.

The new dyes when dyed in the presence of an alkali metal chromate and an ammonium salt, such as ammonium sulfate, furnish on wool blue tints of an excellent fastness to the action of light, to washing and to milling; the same shades being obtained by dyeing on wool mordanted with a chromium mordant or by dyeing wool in an acid bath and treating these tints afterwards with a chromium mordant. In order to illustrate our invention the following examples are given, the parts being by weight:

1. 21.3 parts of 3.4.5-trichloro-2-amino-1-oxybenzene are diazotised by means of 6.9 parts of sodium nitrite and 50 parts of hydrochloric acid of 12° Bé. specific gravity. The diazo compound is allowed to run into a solution of 28.1 parts of 1-acetylamo-8-oxynaphthalene-4-sulfonic acid, alkaline with sodium carbonate. The dyestuff is salted out and worked up as usual. It dyes wool with chromium mordants blue tints of an excellent fastness.

2. The diazo-compound of 21.3 parts of 3.4.6-trichloro-2-amino-1-oxybenzene is coupled with 39.3 parts of 1-toluol-sulfamino-8-oxynaphthalene-4-sulfonic acid in a solution containing sodium carbonate. The dyestuff

separated in the usual manner dyes wool with chromium mordants blue tints.

3. The diazo compound of 19.2 parts of 4-methyl-3.5-dichloro-2-amino-1-oxybenzene is united with a solution of 28.1 parts of 1-acetylamo-8-oxynaphthalene-4-sulfonic acid, alkaline with sodium carbonate. The dye is worked up in the usual manner; it dyes on wool with chromium mordants reddish blue tints.

It is obvious to all skilled in the art that our present invention is not limited to the foregoing examples nor to the details given therein.

What we claim is,—

1. The new ortho-oxyazo dyes which form in the dry pulverized shape of their sodium salts dark powders soluble in water with blue to violet color, from which an acid separates a violet-red precipitate, the aqueous solution becoming more reddish by addition of sodium carbonate and red by addition of sodium hydroxide, yielding upon reduction a polyhalogen-2-amino-1-oxy-derivative of the benzene series and a mono-acidyl-diaminoxyphthalene-sulfonic acid, dyeing on wool in the presence of an alkali metal chromate and an ammonium salt, such as ammonium sulfate, blue tints of an excellent fastness, the same shades being obtained by dyeing on wool mordanted with chromium mordants or by dyeing wool in an acid bath and treating them afterwards with chromium mordants, these dyes which may be obtained by combining a polyhalogen-2-diazo-1-oxyderivative of the benzene series with an acidyl-amino-oxynaphthalene-sulfonic acid.

2. The new ortho-oxyazo dyes which form in the dry shape of their sodium salts dark powders soluble in water with blue to violet color, from which an acid separates a violet-red precipitate, the aqueous solution becoming more reddish by addition of sodium hydroxide, yielding upon reduction a polyhalogen-2-amino-1-oxybenzene and a mono-acidylamino-oxynaphthalene-sulfonic acid dyeing on wool in the presence of an alkali metal chromate and an ammonium salt, such as ammonium sulfate, blue tints of an excellent fastness, the same shades being obtained by dyeing on wool mordanted with chromium mordants or by dyeing wool in an acid bath and treating them afterwards with

chromium mordants, these dyes which may be obtained by combining a polyhalogen-2-diazo-1-oxybenzene with an 1-acidylamino-8-oxynaphthalene-sulfonic acid.

- 5 3. The new ortho-oxyazo dyes which form in the dry pulverized shape of their sodium salts dark powders soluble in water with blue to violet color from which an acid separates a violet red precipitate, the aqueous 10 solution becoming more reddish by addition of sodium carbonate and red by addition of sodium hydroxide yielding upon reduction a polychloro-2-amino-1-oxybenzene and 1-acidylamino-7-amino-8-oxynaphthalene-4-sulfonic acid, dyeing on wool in the presence 15 of an alkali metal chromate and an ammonium salt, such as ammonium sulfate, blue tints of an excellent fastness, the same shades being obtained by dyeing on wool mordanted 20 with chromium mordants or by dyeing wool in an acid bath and treating them afterwards with chromium mordants, these dyes which may be obtained by combining a polychloro-2-diazo-1-oxybenzene with 1-acidylamino-8-oxynaphthalene-4-sulfonic acid.
- 25 4. The new ortho-oxyazo dyes which form in the dry pulverized shape of their sodium salts dark powders soluble in water with blue to violet color, from which an acid separates 30 a violet red precipitate, the aqueous solution becoming more reddish by addition of sodium carbonate and red by addition of sodium hydroxide yielding upon reduction a trichloro-2-amino-1-oxybenzene and 1-acidylamino-7-amino-8-oxynaphthalene-5-sulfonic acid, dyeing on wool in the presence 35 of an alkali metal chromate and an ammonium salt, such as ammonium sulfate, blue tints of an excellent fastness, the same shades 40 being obtained by dyeing on wool mordanted with chromium mordants or by dyeing wool in an acid bath and treating them afterwards with chromium mordants, these dyes which may be obtained by combining a trichloro-2-diazo-1-oxybenzene with 1-acidylamino-8-oxynaphthalene-4-sulfonic acid.
- 45 5. The new ortho-oxyazo dyes which form in the dry pulverized shape of their sodium salts dark powders soluble in water with blue 50 to violet color, from which an acid separates a violet-red precipitate, the aqueous solution becoming more reddish by addition of sodium carbonate and red by addition of sodium

um-hydroxide, yielding upon reduction a trichloro-2-amino-1-oxybenzene and 1-acetyl-amino-7-amino-8-oxynaphthalene-4-sulfonic acid, dyeing on wool in the presence of an alkali metal chromate and an ammonium salt, such as ammonium sulfate, blue tints of an excellent fastness, the same shades being obtained by dyeing on wool mordanted with chromium mordants or by dyeing wool in an acid bath and treating them afterwards with chromium mordants, these dyes which may be obtained by combining a trichloro-2-diazo-1-oxybenzene with 1-acetyl-amino-8-oxynaphthalene-4-sulfonic acid.

6. The new ortho-oxyazo dye which forms in the dry pulverized shape of its sodium salt a dark powder soluble in water with blue color from which an acid separates a violet-red precipitate, the aqueous solution becoming more reddish by addition of sodium carbonate and yellowish-red by addition of sodium-hydroxide, yielding upon reduction 70 3.4.6-trichloro-2-amino-1-oxybenzene and 1-acetyl-amino-7-amino-8-oxynaphthalene-4-sulfonic acid, dyeing on wool in the presence of an alkali metal chromate and an ammonium salt, such as ammonium sulfate, blue 80 tints of an excellent fastness, the same shades being obtained by dyeing on wool mordanted with chromium mordants or by dyeing wool in an acid bath and treating them afterwards with chromium mordants, this dye which 85 may be obtained by combining 3.4.6-trichloro-2-diazo-1-oxybenzene with 1-acetyl-amino-8-oxynaphthalene-4-sulfonic acid and which corresponds as free acid to the formula:

In testimony whereof we affix our signatures in presence of two witnesses.
